E. H. PETERSEN

WASHING MACHINE

Filed July 31, 1922

Inventor:
Ernest H. Petersen
By Fischer & Fagaard
his Attorneys.

UNITED STATES PATENT OFFICE.

ERNEST H. PETERSEN, OF ST. PAUL, MINNESOTA.

WASHING MACHINE.

Application filed July 31, 1922. Serial No. 578,548.

My invention relates to washing machines and has for its object to provide a washing machine consisting of a tub with a support therefor, such that the tub may be 5 rocked to and fro to cause the articles within the same to be tumbled about within the tub and thereby cleansed.

Another object is to form the tub of a flat elongated shape with the ends of the 10 same formed with circular curves so that the water within the machine is caused to travel around the said curves and to completely change directions so as to strike downwardly upon the clothes within the 15 tub, thereby more efficiently cleansing the same.

A still further object is to form a tub with a flat bottom having a plurality of corrugations or slats across the same, for permitting the clothes to slide along the bottom as the tub is rocked, thereby rubbing the clothes.

A still further object is to provide a base for supporting the machine, having a pair 25 of rails and to provide runners attached to the sides of the tub adapted to rest upon the said tracks.

Another object is to provide complementary cam members at the center of said tracks 30 and runners, cooperating with one another to hold the tub in oscillating position upon the tracks.

A still further object of the invention is to provide resilient bumpers at the end of 35 the runners, adapted to engage the ends of the track when the tub reaches its extreme position.

The full objects will be found in the detailed description thereof, and are particularly pointed out in the claims.

In the drawings forming part of the specification:

Figure 1 is a side view of my invention.

Figure 2 is a view similar to Figure 1 45 with parts cut away to show the interior construction of the tub and illustrating the tub in an inclined position.

Figure 3 is an end view of the invention showing a portion of the same in sections.

In the construction of hand operating washing machines it is desirable to produce a machine which requires a minimum amount of exertion to operate and which will effectively cleanse the clothes placed 50 within the same. My invention produces

these results by the employment of a single tub adapted to be rocked upon rockers much in the manner of a rocking chair, which tub is provided with a handle for manipulating the same.

My invention proper consists of an oscillating tub A which is mounted upon a frame B. The frame B consists of two castings 10 and 11 which are formed with rail portions 12 extending across the same and 65 with flanges 13 connecting with said rail portions. At the ends of the castings 10 and 11 are braces extending downwardly as indicated at 14. Along the portions 14 and castings 10 and 11, I provide ribs 15 which 70 are arranged in inclined relation to the rails 12. The ribs 15, braces 14 and flanges 13 serve to support the legs 16 which are rigidly bolted thereto by bolts 17. In addition to the castings 10 and 11 for holding legs 75 16 in place, I provide two cross rails 18 and 19 which are screwed to the said legs 16 by screws 20, immediately below the ribs 15 of the castings 10 and 11. With this 80 construction a rigid framework is provided which is exceedingly simple and which firmly supports the tub as will be presently described.

The tub A which forms a portion of my invention is shaped as best shown in Figures 85 2 and 3. This tub is formed with a flat bottom 21 and a top 22 arranged in parallel relation to one another. The said top and bottom are connected by means of curved ends 23 and 24 which may be curved 90 to conform to a semi-circle or any similar curve. Along the edges of the top 22 and bottom 21 and ends 23 and 24, I attach two side members 25 and 26 which are secured thereto, to form a water tight container. I 95 prefer to construct the tub A of sheet metal, though the same may be constructed of wood if desired. Along the center of the top 22 the same is formed with an opening 27 through which the clothes may be inserted 100 into the tub. Along the edges of this opening, the metal of the sides and top is bent over to form a flange 28 and a seat 29 upon which a cover 30 may be placed. Cover 30 is loosely positioned upon the seats 29 and remains in place during the washing 105 operation without being secured to the tub proper, but if desired fastening means of ordinary construction may be employed. The flange 28 which extends around the opening 110

27 serves to prevent any water which may pass by the cover 30, from leaving the machine.

- For supporting the tub upon the frame B, I provide two runners 31 and 32 which are formed with flanges 33, adapted to lie flush against the sides 25 and 26 of tub A and which have issuing outwardly therefrom, rockers 34 adapted to rest upon and rock upon the rails 12 of the frame B. Runners 31 and 32 have attached to the lower portions of the flanges 33, at the center of the tub, a V-shaped cam member 35 having internal cam surfaces 36, best shown in Figure 1. A lug or pin 37 cast integral with the edge of the rail 12 is adapted to engage the cam walls 36 so as to hold the center rockers 34 centrally positioned upon the tracks 12. The cam walls 36 are so curved that as the tub A rocks upon its support, the lug 37 follows along the walls 36 of cam 35 without appreciable friction against the same. I have discovered that when only one cam member 35 is employed that when the tub A is vigorously rocked, the rocker 34 creeps upon the track 12 so that when the tub A is in the position shown in Figure 2, the lug 37 has left the cam wall 36 which it was following and is positioned between the two cam walls. When the tub rocks back into normal position this naturally causes the lug 37 to engage the opposite cam wall, thereby forcing the rocker 34 to slip upon the rail 12 so that the tub can again assume normal position with lug 37 in contact with its respective cam wall.
- The sliding of the tub along the track is highly undesirable, as a greater amount of energy is required to operate the same than where the tub remains centrally upon the track. For overcoming this difficulty, I provide another cam member 38 which is integrally connected with the castings 10 and 11, near the center thereof. This member is formed with cam walls 40, which are similar to the cam walls 36 of the cam 35 and the said walls are adapted to engage a lug 41 attached to the runners 31 and 32. With this construction the tub cannot be moved longitudinally along the tracks 12 in either direction of the same, regardless of the position of the same relative thereto. This is due to the fact that lug 41 holds it from movement in one direction, while the lug 37 holds it from movement in the other direction. With this device the energy required for operating the machine is greatly reduced, thereby making the invention exceedingly easy to operate.
- For attaching the runners 31 and 32 to the tub A, I provide them with a number of depending hooked brackets 42, which are formed integral with the flanges 33 and which extend below the bottom of the said tub and the edges thereof. Through the

lower portion of the two cams 35 of runners 31 and 32, I pass a rod 43 upon which is screwed two nuts 44, serving to clamp the members 31 and 32 in place. In addition to this rod, I provide two up-standing rib braces 45 which are provided with loops 46 in which a handle 47 may be set. A bolt 48 passing through the upper loop 46 for holding the handle 47 in place, also passes through the side 25 of tub A to rigidly hold the upper end of the runner 31 attached to the tub proper. In this manner it can be clearly seen that the runners are attached to the tub so that leakage of water from the tub is absolutely prevented.

For terminating the movement at each end of the oscillation of the tub and for assisting in reversing the same, I provide two resilient bumpers best shown in Figures 1 and 2. Attached to the ends of the rockers 34 I provide bosses 49 which are arranged to be spaced above the bottom of said rockers. Through these lugs are slidably mounted bolts 50 which have coil springs 51 encircling the same. When the heads of these bolts strike the tracks 12 the coil springs 51 are compressed, thereby retarding the movement of the tub and aiding in reversing the direction of travel of the same. In this manner the tub is caused to rock in a very easy manner so that little exertion is required to operate the machine. For draining the water from the tub a drain 200 is provided.

My improved washing machine is exceedingly simple in construction and having few parts to the same which do not readily get out of order. Due to this fact the machine will last a long time giving the required service throughout its life. Due to the shape of the tub the energy imparted to the water within the same causes the clothes within the same to be thoroughly cleansed with a minimum amount of work. By arranging the tub on rockers and providing the resilient bumpers, the tub is very easily operated and requires a small amount of work to operate it.

Furthermore, the shape of the tub causes the clothes to slide along the corrugated bottom of the tub and to be rubbed in the course of movement across the same. When the clothes and water reach the end of the tub the circular smooth ends cause the clothes to follow freely along the same until the entire mass is turned over and caused to fall downwardly upon the bottom of the tub. This has the effect of thoroughly cleansing the clothes by forcing the water through them and drawing the clothes to the other end where the same operation is repeated.

The clothes are placed into the tub through the opening 27 and the same filled with water to a level, reaching about a third of the height of the same. Upon rocking

the tub upon the rockers 34 the water within the tub is caused to travel along the bottom of the same, passing over and through the clothes in the said tub. To rub the clothes while sliding along the bottom, I provide a plurality of corrugations 60 which are attached, or formed in the tub bottom. As the water and the clothes strike the curved ends 23 and 24 of the tub the movement of the same is reversed in direction and which causes the same to impinge downwardly upon the bottom 27. In this manner the force of the water causes the same to penetrate through the clothes thereby removing the dirt from the same. In this manner it can readily be seen that all of the energy of the water is utilized for the purpose of cleansing the clothes.

In accordance with the patent statutes I have described my invention, illustrating the best embodiment thereof, but I desire to have it understood that the invention can be carried out by other means and applied to uses other than those above set forth within the scope of the following claims:

I claim:

1. A washing machine comprising a frame, a tub, rockers secured to said tub adapted to ride upon said frame, a cam member secured to said rocker, a cam lug secured to said frame and adapted to operate with said cam member, a second cam secured to said frame and a second cam lug secured to said rocker, adapted to operate with said second cam, said cams and lugs operating in conjunction to deprive the tub of longitudinal movement in either direction regardless of the position of the tub relative to the frame.

2. A washing machine comprising a frame, a tub, a runner positioned on each side of said tub, a pair of hook members attached to said runners and adapted to extend beneath the bottom of said tub, and upwardly extending arms connected to said tub, a depending member connected with said runners, a single rod passing through said depending members, below the tub for clamping the members thereto.

3. A washing machine comprising a frame, a tub adapted to rest thereon, said tub having a top and bottom in substantially parallel relation, semi-circular ends connecting said top and bottom, and means including two oppositely disposed notches secured to said frame and tub respectively adapted to cooperate to limit the rocking of the pivot points of said tub.

4. A washing machine including, a pair of rails, a tub, rockers secured to said tub and two oppositely disposed notches secured to said rails and rockers respectively adapted to cooperate to limit the rocking of the pivot points of said tub.

5. A washing machine comprising a frame including a pair of rails, a tub, rockers secured to said tub and adapted to ride upon said rails and pairs of interlocking cam members secured to said rails and rockers for depriving the tub of translatory movement upon the rails.

ERNEST H. PETERSEN.
